(No Model.)

A. V. M. SPRAGUE.
RADIATOR.

No. 512,234.

Patented Jan. 2, 1894.

UNITED STATES PATENT OFFICE.

AUSTIN V. M. SPRAGUE, OF ROCHESTER, NEW YORK, ASSIGNOR TO THE SPRAGUE-SCHUYLER MANUFACTURING COMPANY, OF NEW JERSEY.

RADIATOR.

SPECIFICATION forming part of Letters Patent No. 512,234, dated January 2, 1894.

Application filed March 14, 1893. Serial No. 465,948. (No model.)

To all whom it may concern:

Be it known that I, AUSTIN V. M. SPRAGUE, a resident of Rochester, in the county of Monroe and State of New York, have invented 5 certain new and useful Improvements in Radiators; and I do hereby declare the following to be a full, clear, and exact description of the invention, such as will enable others skilled in the art to which it pertains to make and use 10 the same.

The invention relates to heating by steam, and has for its object to provide an efficient and economical radiator adapted to heat the lower part of a room, closet or receptacle; and 15 it consists in the construction hereinafter described and particularly pointed out.

In the accompanying drawings Figure 1 is a side elevation of the radiator and connections the inclosing walls being in section.

20 Fig. 2 is a plan of a group of radiator sections, certain air passages and radiating pins being for the most part omitted; and Fig. 3 is an enlarged partial section of a radiator.

Numerals 1 denote the side and bottom walls 25 of a chamber of any desired dimensions and may be understood to represent any inclosed space which requires to be warmed.

2, 2 indicate sections of a cast iron radiator made hollow as indicated to receive steam 30 and having transverse openings, 3, for the passage of air. These openings which may be used in any desired number are by preference circular in the plane of the radiator and transversely they have the form of a grooved 35 pulley or approximately that of an hour glass. Around these openings on each flat side of the radiator are arranged projections or pins 4, 4, adapted to conduct and radiate heat.

40 The several radiator sections are each provided with an inlet tube or nipple 6 and an outlet nipple 5. The former are adapted to be coupled with a live steam pipe 8 and the latter with a pipe 7 to carry away the exhausted or condensed steam. These pipes 45 can be extended indefinitely and coupled with as many radiator sections as desired. The sections are inclined slightly in an upward direction from the exhaust to the inlet end 50 to facilitate the escape of the water of condensation. Each section is provided with

supporting legs of suitable length cast preferably integral with the same, and for this purpose the projections 4, 4, or a small number of them made of suitable length may be 55 utilized. These supporting legs may be made of such relative length that one end of each radiator section will be held higher than the other by two, three or more inches to provide proper drainage. If however the legs were 60 made of uniform length the sections could be 65 suitably adjusted by other means.

It is obvious that steam could be admitted and the water of condensation removed from the same end or side of the radiator and such arrangement is contemplated by the invention.

9 indicates an air inlet which may be formed in the side or bottom of the chamber or provided in any preferred way.

70 10 denotes a baffle plate, wall or partition behind which is situated a ventilating flue or flues 12. As shown in Fig. 1 the plate 10 extends a little above the highest point of the radiator and the mouth of the ventilator is situated below said point. This flue is preferably near or within an external wall which is normally the coolest one whereby it tends to cool and condense the adjacent air in the room or compartment and thus promote a 80 downward circulation in said room, the up draft in the ventilating pipe being aided if necessary by any usual means.

75 The operation of the construction is as follows: The radiator sections being arranged and coupled to pipes as described, live steam is admitted and circulated through the radiator the spent steam passing away through the proper pipe. At the same time air is admitted at the inlet or inlets 9 and flows along 90 under the radiator in contact with its radiating pins. Portions of air rise through the successive openings 3. These are surrounded by the projections 4 which conduct heat from the interior of the radiator sections and radiate it externally. They are also subject to transverse or oblique currents of air resulting from the expansion caused by the heating effect of the metal about the holes the latter being of an approximately hour-glass 95 shape as represented whereby counter currents or eddies are promoted and the air 100

brought in more effective contact with the metal. The effect of this upon the steam is to condense it especially along the bottom of the radiator and about the openings, thereby heating the inflowing air. The horizontal progress of the fresh air is checked by the wall 10 and rises through the radiator heated and expanded. By this construction and arrangement the lower part of the chamber is more thoroughly heated than by ordinary devices, an effect to be desired since the tendency of warm air is to ascend and give place below to cooler air so that it is more difficult to keep the lower strata sufficiently warm.

15 The improved radiator can, if desired, be situated below the level of the floor of the chamber it is designed to heat, suitable provision in the construction of the floor being made. The heated air as it ascends becoming moist and foul is cooled by contact with the walls of the room and with objects therein and will ultimately descend near the external or coldest wall. If a mouth of a ventilating flue be placed near the foot of such 20 wall it will promote this circulation. Such a ventilating exit is indicated at 12 below the level of the radiator and separated therefrom by a baffle wall as above stated which wall surrounds the radiator though separate walls 25 will not be required if the radiator is placed in close proximity to the walls of the room or compartment.

30 Having thus fully described my invention, what I claim is—

35 1. The flat oblong radiator section provided

with means for supporting it flatwise on a floor or base having inlet and outlet nipples whereby it may be coupled with inlet and outlet pipes and having transverse air openings and means for supporting the inlet end 40 of the section at a higher level than the other, combined with an air inlet below its lower end and a baffle plate at its higher end and sides, substantially as set forth.

2. The flat oblong radiator section provided 45 with means for supporting it flatwise on a floor or base having inlet and outlet nipples whereby it may be coupled with inlet and outlet pipes and having transverse air openings, radiating projections grouped about said 50 openings and means for supporting the inlet end of the section at a higher level than the other consisting of one or more of said projections made longer than the others, substantially as set forth.

3. A chamber or receptacle, a radiator placed near the chamber floor and practically co-extensive with the same and provided with vertically disposed air openings, an air inlet on one side of the chamber, a baffle plate near 60 the opposite side and an exhaust flue having its mouth behind said baffle plate, substantially as set forth.

In testimony whereof I have signed this specification in the presence of two subscribing witnesses.

AUSTIN V. M. SPRAGUE.
